RAILWAY CROSSTIE ANTICHECK

Charles L. Wickersham, Pittsburgh, Pa., and
Jacob Alvin Hyle, Detroit, Mich.

Application June 20, 1944, Serial No. 541,144

7 Claims. (Cl. 85—11)

This invention relates to a means to prevent railway cross ties from checking or splitting.

An object of this invention is to provide an anti-splitting means of this kind which is of simple construction and will not materially add to the cost of the cross ties.

Another object of this invention is to provide an anti-splitting means of this kind which can be installed at the time the cross ties are being prepared for creosoting, the installation being an exceedingly simple operation so that the preparation of the cross ties to receive the anti-splitting means will not delay the handling of the cross ties during the creosoting thereof.

A further object of this invention is to provide an anti-splitting means which is mounted in the ends of the cross ties, being wedged into slots or recesses formed in the ends of the cross ties, the anti-splitting means including a pair of parallel plates and a locking bar for holding the plates against outward and lateral movement.

With the foregoing objects and others which may hereinafter appear, the invention consists of the novel construction, combination and arrangement of parts as will be more specifically referred to and illustrated in the accompanying drawing, wherein is shown an embodiment, but it is to be understood that changes, modifications and variations may be resorted to which fall within the scope of the invention as claimed.

In the drawing:

Figure 1 is a detail end elevation of a railway cross tie having an anti-check device constructed according to an embodiment of this invention mounted therein.

Figure 2 is a fragmentary sectional view taken on the line 2—2 of Figure 1.

Figure 3 is a fragmentary sectional view taken on the line 3—3 of Figure 1, and

Figure 4 is an exploded perspective view of the anti-check elements removed from the rear tie.

Referring to the drawing, the numeral 10 designates generally a railway cross tie of the type which is normally impregnated with creosote or other preserving means and is secured in the normal manner beneath the rails. The tie 10 under normal conditions has a tendency to split lengthwise thereof and in a vertical direction thereby shortening the life of the tie even though the wood forming the tie is in condition where it might be used for a number of additional years.

In order to provide a means whereby the tie 10 will be held against splitting, we have provided a pair of substantially semi-circular recesses 11 and 12 extending into each end of the

tie in spaced relation to each other and inwardly from the opposite vertical sides of the tie. A pair of substantially semi-circular plates 13 and 14 are adapted to be forced into the openings 11 and 12, these openings being of such a width that it will be necessary to forcibly press the plates 13 and 14 into these openings.

The tie 10 has cut in each end thereof a horizontally disposed slot 15 which extends across and intersects the openings 11 and 12. A locking member generally designated as 16 is adapted to be pressed or otherwise forced into the slot 15 and as shown in Figure 4 the locking member 16 is formed of a longitudinally bowed flat bar 17 having formed integral with the opposite ends thereof a pair of jaw members 18 and 19.

The inner edge 20 of the jaw member 18 is adapted to engage against the outer side of the plate 13 whereas the inner edge 21 of jaw member 19 is adapted to engage against the outer side of plate 14. Plate 13 is formed with an outwardly opening slot 22 within which the adjacent portion of the bar 17 is adapted to engage and the plate 14 with a slot 23 within which the adjacent portion of bar 17 is adapted to engage so that the outer edge of the bar 18, when in applied position, will be flush with the outer straight edges 24 and 25 of plates 13 and 14, respectively.

Jaw member 18 has struck therefrom a tang 26 and jaw member 19 has struck therefrom a tang 27. These tangs are adapted to bite into the adjacent side of the openings or slot 15 and thereby hold the bar 17 with the jaws 18 and 19 against outward movement with respect to the tie 10.

In the application of the anti-checking means on the rail tie, the tie is initially formed with the openings or slots 11 and 12 by means of a pair of rotating saw blades of disc-shape which are spaced apart the desired distance and are mounted on a common shaft. The two openings 11 and 12 can be formed in a single operation, whereupon the transverse horizontal slot 15 may be cut entirely across the end of the tie. The plates 13 and 14 may then be driven into the openings 11 and 12, the slots 22 and 23 registering with the slot or opening 15 of the tie 10. The longitudinal bowed clamping bar 17 is then pressed or otherwise forced into slot 15. The bowing of bar 17 provides a means to more firmly hold bar 17 against outward movement lengthwise of the rear tie 10.

The outwardly directed tangs 26 and 22 which are carried by the jaws 18 and 19 will bite into the adjacent side of slot 15 so that these jaws 55 with bar 18 will be held against movement length-

wise of the tie. Bar 17 when in applied position is held against horizontal movement laterally of the tie by means of jaws 18 and 19 engaging the opposite faces of plates 13 and 14.

With a construction of this kind, in the event the rail tie should split vertically at a point between the plates 13 and 14, the tie cannot spread due to the fact that plates 13 and 14 are held against movement relative to each other by the clamping jaws 18 and 19.

This anti-checking or anti-splitting means is mounted in each end of the rail tie and can be so mounted either before or after the tie has been creosoted, or otherwise treated against rot or other damaging elements. The anti-checking or splitting means being formed of only three elements which are preferably stamped or otherwise formed from metal will not appreciably increase the cost of each rail tie, but when applied to the tie will increase the useful life of the tie for a considerable period.

What we claim is:

1. The combination with an elongated wooden member having a pair of spaced apart semi-circular recesses in an end thereof and an elongated slot intersecting said pair of recesses and extending laterally therefrom, a pair of semi-circular plates seated in said pair of recesses and each formed with a slot registering with said first slot, an elongated bar seated in said first slot and engaging in said recesses, and a lug at each end of said bar bearing against the adjacent face of a plate to thereby hold said plates against lateral outward movement.

2. The combination as set forth in claim 1 wherein said bar is formed of resilient material

and is longitudinally bowed whereby to provide for the frictional holding of said bar in said elongated slot.

3. The combination set forth in claim 1 including at least one tang carried by each lug and adapted to bite into a side of said elongated slot to thereby hold said bar and said lugs against outward movement lengthwise of said member.

4. The combination set forth in claim 1 where-
10 in said bar is formed of resilient material and is longitudinally bowed whereby to provide for the frictional holding of said bar in said elongated slot, and each lug includes an offset tang adapted to bite into a side of said elongated slot to hold
15 said bar and said lugs against outward movement.

5. As a new article of manufacture, an anti-
10 checking means for rail ties comprising a pair
of semi-circular plates adapted to be embedded
in an end of a rail tie with the straight edge out-
20 ermost, each plate having a slot in the outer
edge thereof, and a clamping member substan-
tially U-shaped in plan having the bight thereof
engageable in said slots and the legs thereof abut-
ting the outer sides of said plates.

6. An anti-checking means for rail ties as set
forth in claim 5 wherein said plates are of parti-
circular configuration with a straight outer edge.

7. An anti-checking means for rail ties as set
forth in claim 5 including at least one tang struck
30 from a leg and adapted to bite into a side of a
slot formed in the tie to hold said clamping mem-
ber against outward movement lengthwise of the
tie.

CHARLES L. WICKERSHAM.
